JOHN MURDOCK, OF JERSEY CITY, NEW JERSEY, ASSIGNOR TO
JOHN SAVERY'S SONS, OF NEW YORK CITY.

Design No. 3,438, dated March 30, 1869.

DESIGN FOR A BIRD-HOUSE.

The Schedule referred to in these Letters Patent and making part of the same.

To all whom it may concern :

Be it known that I, JOHN MURDOCK, of Jersey City, in the county of Hudson, and State of New Jersey, have invented and produced a new and original Design for a Bird-House; and I do hereby declare the following to be a full, clear, and exact description of the same, reference being had to the annexed drawing, making part of this specification, wherein—

Figure 1 is an elevation of said bird-house;

Figure 2 is a vertical section of one side of the same at the line $x\ x$; and

Figure 3 is a sectional plan at the line $y\ y$, fig. 1.

Similar marks of reference denote the same parts.

The base, a , is made as a beaded "ogee," the lower member being convex and the upper concave.

The body of the house is made with vertical sides, ornamented with convex ribs $b\ b$.

The roof of the house is dome-shaped at c , concaved at d , and with rounding eaves e , scalloped at their edges.

The entrance to the house is made of the projecting flanges $f\ f$, of the ornamental shape and design represented.

What I claim, and desire to secure by Letters Patent, is—

The design, of the ornamental shape and configuration, of the bird-house, substantially as described and represented.

In witness whereof, I have hereunto set my signature, this 27th day of February, 1869.

JOHN MURDOCK.
